UNITED STATES PATENT OFFICE

148,097

DESIGN FOR A CHECKER GAME BOARD

Joseph Sottile, Bronx, N. Y.

Application August 17, 1946, Serial No. 132,617

Term of patent 14 years

(Cl. D34—5)

To all whom it may concern:

Be it known that I, Joseph Sottile, a citizen of the United States, residing at the Bronx, New York, in the county of Bronx and State of New York, have invented a new, original, and ornamental Design for a Checker Game Board, of which the following is a specification, reference being had to the accompanying drawing, forming a part thereof:

In the drawing:

Fig. 1 is a top plan view of a checker game board, showing my new design; and

Fig. 2 is a sectional view, taken on the line 2—2 of Fig. 1.

I claim:

The ornamental design for a checker game board, as shown.

JOSEPH SOTTILE.
